REVERSING SANDER

Charles A. Campbell, deceased, late of Watertown, N. Y., by Carrie E. Campbell, administratrix, Watertown, N. Y., assignor to The New York Air Brake Company, a corporation of New Jersey

Application November 25, 1940, Serial No. 367,142

8 Claims. (Cl. 291—5)

This invention relates to track sanding devices and particularly to such devices for use on railway cars which are operated in both directions.

The present trend is toward the sanding of all braked wheels throughout a train. So far as the present invention is concerned this sanding may be controlled in any suitable way, known means being manual, automatic as an incident to every brake application, and automatic as an incident to emergency applications only. Timing mechanisms have been included in all three types to cause sanding, when started, to continue for definite periods. The present invention imposes no limitation as to the use of any such control.

Where the direction of travel of the car is reversible sanding mechanism must be provided for each direction of travel. The present invention provides a selector to connect the sanding control (sanding relay) of the car selectively in controlling relation with sanding traps appropriate to the direction of travel.

This involves features of novelty in its electro-pneumatic arrangement, in features which inhibit its operation as an incident to reversals during car shifting operations (which would cause useless wear and waste of electric and pneumatic energy) and various other refinements which will appear upon consideration of the preferred embodiment now about to be described by reference to the accompanying drawings.

In the drawings—

Fig. 1 is a diagram of the braking and sanding equipment of one car.

Fig. 2 is a section through the selector valve device with an axial section through the selector switch which controls it. In this view the electrical connections are diagrammed.

Fig. 3 is a section through the selector switch on the line 3—3 of Fig. 2.

In the drawings, the arrow F indicates forward and the arrow R reverse directions of running. These terms are merely relative and used to permit differentiation of two relatively reverse functions as to sanding.

A desirable arrangement, indicated in Fig. 1, is to sand ahead of the rear truck of the car, because this brings the sanding close to the leading truck of the next succeeding car and thus gives a better result than can be had by sanding ahead of the leading truck of a car whose two trucks are separated by a much greater interval.

In Fig. 1 the automatic brake pipe is indicated at 11. It has the usual angle cocks 12 and connecting hose 13. Conductors valves are shown at

14. A control valve of the well known D-22 type is indicated at 15. The auxiliary and emergency reservoirs are combined in the shell 16 and the displacement chamber appears at 17.

The control valve 15 charges the auxiliary and emergency reservoirs and the supply reservoirs 18 during release and running conditions with air derived from the brake pipe, as is well understood. In response to reduction of brake pipe pressure it establishes appropriate controlling pressures in relay 19 which in response thereto admits compressed air from supply reservoirs 18 to brake cylinders 21. Restoration of brake pipe pressure reestablishes release conditions according to principles familiar in the air brake art.

A sanding air supply reservoir 22 is charged in unison with reservoirs 18 but is isolated therefrom during brake applications by an intercepting valve 23 so that braking air can never be drawn upon for sanding while an application of the brakes is in effect. Reservoir 22 supplies sanding air to a relay 24. Relay 24 may be of any suitable type and only its function need be stated. The particular relay shown responds to the disclosure in application Serial No. 338,387, filed June 7, 1940. The traps conform to the disclosure in application Serial No. 314,173, filed January 16, 1940, and issued as Patent No. 2,243,243.

So far as is material to the present invention, the relay 24 operates as follows: Normally inactive, it may be rendered active by emergency response of control valve 15, which then admits air under pressure to pipe 25. It may also be put into action by energization of train circuit 26—27, controlled from the head of the train in any preferred way. The jumpers 28 provide inter-car connections for the train circuit. A magnet valve forming part of relay 24 and connected to branch leads 29—29 causes the relay to operate when the circuit is energized.

When the relay goes into action it supplies air to the cleanout air pipe 31, then to the sanding air pipe 32 (cutting off the supply to 31). As it goes out of action it cuts off the supply to pipe 32 and delivers a brief blast to cleanout pipe 31 to clear out residual sand.

With such a relay special traps are used. The forward set of traps 33F and the rear set 33R have each a cleanout pipe 34F, 34R and each a sanding air pipe 35F, 35R.

No novelty is here claimed for the apparatus so far described. It is typical of known practice (except as to provision for reversal) and the details are subject to wide variation. For example,

the design of relay 24 depends on the design of the traps 33F, 33R.

The function of the selector is to connect 34F or 34R selectively with cleanout air pipe 31 and at the same time connect 35F or 35R with sanding air pipe 32. The selector is generally indicated by numeral 36 in Fig. 1.

The selector 36 is shown in detail in Fig. 2 to which reference should now be made. The supporting component is a bracket 37 to which all pipe connections are made. These comprise air supply pipe 38 from reservoir 22 and pipes 31, 32, 34F, 35F, 34R, 35R, above described. Passages forming extensions of these pipes are given the same identifying numerals.

On the right side of bracket 37 is the forward magnet valve assembly generally indicated at 39F and the reverse magnet valve assembly 39R. Bolted to the left side is housing 41 which encloses the cleanout reversing unit 42, the sanding air reversing unit 43, and a piston operated slide valve which controls units 42 and 43 and is itself shifted reversely by momentary excitations of magnet valves 39F, 39R respectively. The slide valve unit remains in either of its two positions after response to such momentary excitations and positions positively the large capacity poppet valves of units 42 and 43. Thus stability of the slide valve is combined with large flow capacity characteristics of poppet valves.

Fig. 2 shows the parts in what is called "forward" position, i. e., travel in direction of arrow F of Fig. 1.

The main valve of unit 42 is a double faced check valve 44 in a chamber 45 to which cleanout pipe and port 31 lead. The valve has oppositely extending pilots which guide it in the opposed seats 46 and 47. It is biased toward the latter by spring 48. Pipe and passage 34F communicate through seat 46 and 34R through seat 47. Thus pipe 31 is connected to 34F for forward running (as shown) and to 34R for reverse running, in which case spring 48 must be overpowered so that valve 44 closes against seat 46.

To shift the valve 44 against the opposition of spring 48 use is made of a diaphragm motor. The diaphragm 49 of this motor is clamped at its periphery about a recess in body 41 by a recessed cap 51. The diaphragm is of the annular fold or slack type and carries clamped to its center a thrust disc or hub 52. A tubular stem 53 fixed in hub 52 houses a thrust plunger 54 which is yieldingly sustained by coil compression spring 55. The stem is closely confined in a guide, as shown, and when the hub 52 is forced upward a gasket 56 seals around the guide to prevent leakage from passage 34R around the stem. This is needed because the space above the diaphragm is vented to atmosphere by port 57. The spring 55 permits full traverse of hub 52 assuring tight sealing of gasket 56 and valve 44.

The unit 43 is identical with unit 42 and the corresponding parts thereof are given the same numbers with the distinguishing letter S.

Formed in the body 37 is a slide valve chamber 58 to which the reservoir pipe and passage 38 supply air at sanding reservoir pressure. At opposite ends of the valve chamber are cylinders 59 and 61 which communicate with the chamber 58 and are of equal diameters. A pair of pistons 62 and 63, connected by a stem 64, work in these cylinders and the stem is notched to confine a slide valve 65. In the seat for the slide valve are two ports, an exhaust port 66 connected with

a branch of passage 57 and a port 67 connected with the spaces below the diaphragms 49 and 49S.

When the pistons are to the left in forward running position, as shown, piston 62 seals against a gasket, as shown, and a cavity 68 in slide valve 65 connects ports 66 and 67, exhausting the spaces below the two diaphragms 49, 49S so that springs 48, 48S position the valves 44, 44S as shown. When the pistons are to the right (reverse running position) piston 63 seals on a gasket and valve 65 isolates port 66 and exposes port 67 to pressure in chamber 58. This pressure reacting on diaphragms 49, 49S forces valves 44, 44S to their upper positions to connect pipes 34R, 35R instead of 34F, 35F with pipes 31 and 32.

Each piston 62 and 63 has a small through port as shown, to permit pressure equalization to occur slowly, so that the pistons are normally inert but either will become active if the space at its outer side be rapidly vented. The unit 39F performs this function for the space to the left of piston 62 and 39R for the space to the right of piston 63.

Referring first to 39F, chamber 71 is connected by passage 72 with the space to the left of piston 62. In the chamber 71 is a double beat poppet valve 73 which seats upward to close an exhaust port 74 toward which it is biased by spring 75. When forced downward it opens the exhaust port 74 and closes a normally open supply port 76 leading from chamber 77 to which a branch of reservoir passage 38 leads. The double beat poppet valve 73 is shifted when winding 78 is energized to force downward an armature (not shown) carried by valve stem 79.

Corresponding parts of unit 39R are similarly numbered with the distinguishing letter R. The passage 72R leads, of course, to the space to the right of piston 63.

Brief excitation of winding 78 or 78R (1/2 second being a suitable period) will cause response of the corresponding piston 62 or 63 followed by pressure equalization. The supply ports 76, 76R are not strictly necessary and can be omitted but their use is preferred.

A double acting drag switch, or its equivalent, operated by a car axle or by a shaft driven thereby is used to excite the windings 78, 78R selectively and briefly after the car has attained a running speed as contradistinguished from a yard switching speed. Such a switch is shown in Figs. 2 and 3.

A housing 81 is adapted for mounting on a journal bearing cover plate. It includes a cover 82 having an inwardly extending sleeve 83 which supports certain annular ball bearings herein-after described and also the fixed arms 84 and 85. Supported on the bearings 86 and 87 is a shaft 88 with a forked end 89 by means of which it is connected to the journal in the journal box or to any other member which rotates at a speed proportional to car wheel speed. The shaft 88 carries a disc 91 upon which are mounted a series of U-shaped permanent magnets 92 arranged to form alternate north and south poles around the circumference of the disc 91.

Mounted on bearings 93, which are supported on the outer side of the sleeve 83, is a flanged disc 94. The flanged portion of the disc is deeply slotted at uniform intervals to receive copper rivets 95 which connect two copper bands 96 and 97, one on the inner side and the other on the outer side of the flange. This construction

provides short circuited turns around successive segments of the flange of the disc. The permanent magnets rotate with the driven shaft within these segments and separated from them by a small air gap.

Mounted on the drum 94 are two spring plungers assemblies 98 and 99 which react against the arm 84 in opposite directions and tend to define a neutral position for the disc 94. The resistance developed by these spring plungers is adjustable by means indicated in the drawings. Motion of the disc is limited by stops 100 which are mounted on the disc and engage the arm 85.

Mounted on the arm 84 are three brushes 101, 102 and 103. These coat with two contact strips 104 and 105 whose form is clearly shown in the drawings. These strips are mounted on an insulating block 106 carried by disc 94 and the parts are so arranged that brush 101 always contacts strip 104, brush 102 always contacts strip 105, while brush 103 will contact selectively with the strips 104 and 105 upon displacement of the disc from its mid position and will overtravel these contacts in the extreme position of the disc.

Brush 101 is connected with the winding 78 and brush 102 with the winding 78R, while brush 103 is connected with one terminal of a battery 107 whose other terminal is connected to complete circuits through the windings 78 and 78R. The rotary system of magnets reacts reversely on the disc 94, depending on the direction of motion of the car and as car speed rises will close and then open a circuit through a selected one of the windings 78 or 78R, depending upon whether the car is moving forward or reversely. The position of the parts as shown in Fig. 2 is that which is assumed as the result of energization of the winding 78. The circuit is closed briefly at forward and reverse speeds which are high enough to be outside the ordinary range of car shifting operations. It is undesirable to have the selector operate uselessly during yard shifting of the car and the desired results can be secured by the means described. However, the selector becomes effective at speeds low enough to produce the desired selection at any speed at which sanding on the train would be needed.

It is claimed:

1. In a track sanding system for railway cars adapted to run in opposite directions, the combination of two pneumatically operated sanding units, one for one and the other for the opposite direction of running; a sanding relay for controlling the supply of operating air to such sanding units; a selector valve mechanism having two alternative settings in which respectively it connects said sanding relay selectively in controlling relation with one or the other sanding unit; and means responsive to motion of the vehicle above a certain speed in relatively opposite directions and arranged to cause shifting of said selector valve mechanism between said alternative settings according to the direction of running.

2. In a track sanding system for railway cars adapted to run in opposite directions, the combination of two pneumatically operated sanding units, one for one and the other for the opposite direction of running; a sanding relay for controlling the supply of operating air to such sanding units; a selector valve mechanism having two alternative settings in which respectively it connects said sanding relay selectively in controlling relation with one or the other sanding unit; means responsive to motion of the vehicle in relatively opposite directions to cause shifting of said

selector valve mechanism between said alternative settings; and means serving to delay the action of said responsive means until a vehicle speed is attained higher than that normally used in shifting operations whereby the selector valve is protected from undue wear.

3. In a track sanding system for railway cars adapted to run in opposite directions, the combination of two pneumatically operated sanding units, one for one and the other for the opposite direction of running; a sanding relay for controlling the supply of air to such sanding units; a pressure motor operated selector valve mechanism of large flow capacity for connecting said relay selectively with said sanding units; a pilot slide valve having two positions in which respectively it conditions the pressure motor of said selector valve mechanism to connect different ones of said two units; two electro-pneumatic means, each of which is adapted when excited for a brief period to shift said slide valve to a corresponding one of said two positions; and controlling means responsive to motion of the car above a certain speed and adapted to excite said electro-pneumatic means selectively according to the direction of running.

4. In a track sanding system for railway cars adapted to run in opposite directions, the combination of two pneumatically operated sanding units, one for one and the other for the opposite direction of running; a sanding relay for controlling the supply of air to such sanding units; a pressure motor operated selector valve mechanism of large flow capacity for connecting said relay selectively with said sanding units; a pilot slide valve having two positions in which respectively it conditions the pressure motor of said selector valve mechanism to connect different ones of said two units; two electro-pneumatic means, each of which is adapted when excited for a brief period to shift said slide valve to a corresponding one of said two positions; and controlling means responsive to the attainment of definite car speeds in opposite directions to excite said electro-pneumatic means respectively according to the direction of running.

5. In a track sanding system for railway cars adapted to run in opposite directions, the combination of two pneumatically operated sanding units, one for one and the other for the opposite direction of running; a sanding relay for controlling the supply of air to such sanding units; a pressure motor operated selector valve mechanism of large flow capacity for connecting said relay selectively with said sanding units; a pilot slide valve having two positions in which respectively it conditions the pressure motor of said selector valve mechanism to connect different ones of said two units; two electro-pneumatic means, each of which is adapted when excited for a brief period to shift said slide valve to a corresponding one of said two positions; and controlling means responsive to motion of the car in both directions and effective within limited speed ranges in each direction to excite respective electro-pneumatic means according to the direction of running.

6. In a track sanding system for railway cars adapted to run in opposite directions, the combination of two pneumatically operated sanding units, one for one and the other for the opposite direction of running; a sanding relay for controlling the supply of operating air to such sanding units; an electrically controlled pneumatically actuated selector valve mechanism for

selectively connecting said relay with said sander units; switching means serving to control said selector mechanism; and means for operating said switching mechanism reversely in response to running of the car above a certain speed in relatively reverse directions.

7. In a track sanding system for railway cars adapted to run in opposite directions, the combination of two pneumatically operated sanding units, one for each direction of running, each such unit having a cleanout air connection and a sanding air connection; a sanding relay having connections for controlling the supply of air to the cleanout and to the sanding air connections of such units; two pressure motor operated selector valve mechanisms, each of large flow capacity, one for connecting the cleanout air connection of the relay respectively with the cleanout connections of the two units selectively and the other for connecting the sanding air connection of the relay respectively with the sanding air connection of the two units selectively; a pilot valve arranged to control the pressure motors of said selector valve mechanisms in unison, said pilot valve having two distinct functional positions, one for forward and the other for reverse running, and in each of which the valve tends to remain unless positively actuated; two electrically actuated normally inert means for shifting said pilot valve reversely between said functional positions; and controlling means responsive to running of the car above a certain speed in opposite directions to actuate said electrically actuated means selectively according to the direction of running.

8. In a track sanding system for railway cars adapted to run in opposite directions, the combination of two pneumatically operated sanding units, one for each direction of running, each such unit having a cleanout air connection and a sanding air connection; a sanding relay having connections for controlling the supply of air to the cleanout and to the sanding air connections of such units; two pressure motor operated selector valve mechanisms, each of large flow capacity, one for connecting the cleanout air connection of the relay respectively with the cleanout connections of the two units selectively and the other for connecting the sanding air connection of the relay respectively with the sanding air connection of the two units selectively; a pilot valve arranged to control the pressure motors of said selector valve mechanisms in unison, said pilot valve having two distinct functional positions, one for forward and the other for reverse running, and in each of which the valve tends to remain unless positively actuated; two electrically actuated normally inert means for shifting said pilot valve reversely between said functional positions; and controlling means responsive to running of the car above a certain speed in opposite directions to actuate said electrically actuated means selectively according to the direction of running, said controlling means including a relay selectively connecting said pilot valve with the electrically actuated means, and including means for operating said relay reversely in response to running of the car above a certain speed in relatively reverse directions.

adapted to run in opposite directions, the combination of two pneumatically operated sanding units, one for each direction of running, each such unit having a cleanout air connection and a sanding air connection; a sanding relay having connections for controlling the supply of air to the cleanout and to the sanding air connections of such units; two pressure motor operated selector valve mechanisms, each of large flow capacity, one for connecting the cleanout air connection of the relay respectively with the cleanout connections of the two units selectively and the other for connecting the sanding air connection of the relay respectively with the sanding air connection of the two units selectively; a pilot valve arranged to control the pressure motors of said selector valve mechanisms in unison, said pilot valve having two distinct functional positions, one for forward and the other for reverse running, and in each of which the valve tends to remain unless positively actuated; two electrically actuated normally inert means for shifting said pilot valve reversely between said functional positions; controlling means responsive to running of the car in opposite directions to actuate said electrically actuated means selectively according to the direction of running; and means for delaying the operation of the last named means until the car attains a speed higher than that used in yard shifting whereby useless operation of the selector is minimized.
